United States Patent Office

Des. 183,673
Patented Oct. 14, 1958

183,673

FISH LURE

Robert E. Bateman, Lake City, Pa.

Application May 27, 1957, Serial No. 46,372

Term of patent 14 years

(Cl. D31—4)

FIG. 1

FIG. 2

FIG. 3

Fig. 1 is a side elevational view of a fish lure embodying my new design;

Fig. 2 is a perspective view thereof; and

Fig. 3 is a fragmentary front elevational view of Fig. 1, the hooks, spinners, and beads being omitted for purposes of illustration.

I claim:

The ornamental design for a fish lure, as shown.
